UNITED STATES PATENT OFFICE.

SAMUEL FRIEND, OF DECATUR, ILLINOIS, ASSIGNOR OF ONE-HALF TO
WILLIAM B. CHAMBERS, OF SAME PLACE.

MACHINE FOR SEPARATING GRAVEL FROM CLAY.

SPECIFICATION forming part of Letters Patent No. 409,186, dated August 20, 1889.

Application filed December 7, 1888. Serial No. 292,870. (No model.)

To all whom it may concern:

Be it known that I, SAMUEL FRIEND, of the city of Decatur, county of Macon, and State of Illinois, have invented a certain new and 5 useful Machine for Separating Gravel from Clay, of which the following is a specification.

My invention is designed to separate gravel and other hard substances from clay in a plastic condition; and it consists in the details of 10 construction and combinations of parts hereinafter set forth and claimed.

In the drawings accompanying and forming a part of this specification, Figure 1 is a side elevation of my machine, showing the gearing thereof. Fig. 2 is a vertical section of the machine on a line near its transverse center. Fig. 3 shows the operative parts of the machine in perspective, the gearing and supports being omitted to give an unobstructed 15 view; and Figs. 4, 5, 6, and 7 show details the pertinence of which will hereinafter appear.

The roll *a* is made of an unyielding substance, and it is preferably grooved around its circumference in parallel lines. In Fig. 5 25 a face view of the roll is given, on which the grooves are faintly indicated. In Fig. 7 a fragment of the roll on an enlarged scale enables the grooves to be clearly seen, and they are here identified with reference-letter *a''*.

The roll *b* is closely opposed to roll *a* and 30 its outer surface is made of a yielding substance, as caoutchouc or india-rubber, sufficiently rigid to press the clay firmly against roll *a*. The bearings of the shaft of roll *b* are 35 preferably made yielding, as indicated in Fig. 4 and as will be hereinafter set forth. Rotary frame *c* has beaters *c''*, that in their rotation nearly approach roll *a*. The scraper *d* is set 40 against roll *a* with its edge preferably presented in a direction nearly opposed to the direction of the rotation of the roll, and if the roll is grooved the scraper has teeth adapted to the grooves. In Fig. 6 a scraper is shown 45 with teeth adapted to the grooves of the fragment of roll shown in Fig. 7.

The elements just specified comprise the essentials of the invention, and their operation is as follows: Clay in a plastic condition is supplied to the rolls from above. The rolls 50 and the beater-frame are rotated in the direc-

tion indicated by their respective arrows in Fig. 3, the frame moving more rapidly than the rolls. The clay is pressed into a thin sheet, which adheres to roll *a*. The gravel, &c., depresses roll *b* at the immediate points 55 of contact, and passes between the rolls embedded in the sheet of clay and projecting therefrom. The beaters approach the clay as nearly as possible without touching, and all matter projecting from the clay is struck and 60 removed. As the pure clay comes in contact with the scraper it is also removed from the roll and the operation is completed. The grooves in roll *a* enable the clay to adhere more closely to the roll, and also leave the 65 clay in better condition for the subsequent process of molding. They must be small enough to exclude pieces of gravel, &c., large enough to be detrimental to the clay.

The yielding bearings of the shaft of roll 70 *b* are provided for emergencies only. In case a piece of gravel exceeding in size the yielding capacity of the roll is presented to the machine the bearings will yield to permit its passage; but under ordinary circumstances 75 the rolls will be held to their work in a practically rigid manner and the gravel will effect a passage by depressing the surface of roll *b*. The yielding bearings each comprises a frame *p*, a bearing-block *p'*, adapted to slide in the 80 frame, a spring *p''*, a head *q*, and an adjusting-bolt *q'*, that permits the regulation of the tension of the spring.

Drive-pulley *f* is secured to an end of shaft *a'* of roll *a*. Gear-wheel *g* and sprocket-wheel *h* are secured to the opposite end of the same shaft. Gear-wheel *i* is secured to the shaft *b'* of roll *b* and it meshes with wheel *g*. The teeth of the gear-wheels are sufficiently long to permit yielding motion in the 90 shaft-bearings without disconnecting the wheels. Sprocket-wheel *k* is mounted on the shaft *c'* of the rotary frame *c* *c''*. Chain *l* connects sprocket-wheel *k* with sprocket-wheel *h*. 95

It is desirable that the scraper may be adjustable with relation to roll *a* in order to compensate for wear. Means to this end consist of guides *r r*, fixed bearings *s*, and set-screw *t*, acting on the scraper through bear- 100

ings *s*. The scraper may be composed of the plate *d*, secured to backing *d'*.

The supporting-frame is indicated by reference-letter *m*. Brackets *n* support the bearings of shaft *c'*. A chute *o* acts as a conveyer for the pure clay, and also forms a partition to divide the gravel from the clay. A hopper is shown at *e* in Figs. 1 and 2. In Fig. 2 the yielding substance of roll *b* is shown mounted on cylinder *b''*, which is secured to shaft *b'*. In Fig. 2 the beaters *c''* are shown bolted to lugs *c'''*, which are formed on heads *c*.

By the use of my invention clay originally containing a large proportion of gravel may be readily shaped into articles of use, and be subsequently baked or burned without developing lime injuriously.

Having thus described my invention, I claim as new and desire to secure by Letters Patent—

1. A machine for separating gravel from clay, comprising a non-yielding roll, a yielding roll opposed to the non-yielding roll, beaters in proximity to the non-yielding roll, and a scraper adapted to the non-yielding roll, as set forth.

2. A machine for separating gravel from clay, comprising a non-yielding roll grooved parallelly around its circumference, a yielding roll opposed to the non-yielding roll, beaters in proximity to the non-yielding roll, and a scraper for the non-yielding roll having teeth adapted to the grooves, as set forth.

3. A machine for separating gravel from clay, comprising a non-yielding roll grooved parallelly around its circumference, a roll opposed to the non-yielding roll mounted in yielding bearings and having a yielding external surface, beaters in proximity to the non-yielding roll, and a scraper for the non-yielding roll having teeth adapted to the grooves, as set forth.

4. A machine for separating gravel from clay, comprising rolls *a* and *b*, the one non-yielding, the other yielding, hopper *e* above the rolls, beaters *c''* under roll *a*, and scraper *d* presented to roll *a*, substantially as set forth.

5. A machine for separating gravel from clay, comprising shaft *a''*, carrying roll *a*, drive-wheel *f*, gear-wheel *g*, and sprocket-wheel *h*, shaft *b'*, carrying roll *b* and gear-wheel *i*, the latter meshing with wheel *g*, shaft *c'*, carrying beaters *c''* and sprocket-wheel *k*, chain *l*, connecting sprocket-wheel *k* with sprocket-wheel *h*, hopper *e* above the rolls, and scraper *d* in contact with roll *a*, as set forth.

In testimony whereof I sign my name in the presence of two subscribing witnesses.

SAMUEL FRIEND.
